UNITED STATES PATENT OFFICE.

HARRY S. LIBBEY, OF ARLINGTON, MASSACHUSETTS, ASSIGNOR TO EDWIN STANLEY LIBBEY, OF ARLINGTON, MASSACHUSETTS.

DESIGN FOR A COMBINED GLARE SHIELD AND BRACKET THEREFOR.

Application filed March 3, 1926. Serial No. 16,762. Term of patent 14 years.

To all whom it may concern:

Be it known that I, HARRY S. LIBBEY, a citizen of the United States, and a resident of Arlington, county of Middlesex, and Commonwealth of Massachusetts, have invented a new, original, and ornamental Design for Combined Glare Shields and Bracket Therefor, of which the following is a specification, reference being had to the accompanying drawing.

The figure is a perspective view showing my design.

The glare-shield portion of the article illustrated is regarded as the dominant feature of my design.

I claim:

The ornamental design for a combined glareshield and bracket therefor, substantially as shown.

HARRY S. LIBBEY.
